UNITED STATES PATENT OFFICE.

LEONARD C. BAILEY, OF CHICAGO, ILLINOIS.

TOY.

984,735.

Specification of Letters Patent.

Patented Feb. 21, 1911.

Application filed April 8, 1907. Serial No. 366,941.

To all whom it may concern:

Be it known that I, LEONARD C. BAILEY, citizen of the United States, residing at Chicago, in the county of Cook and State of Illinois, have invented certain new and useful Improvements in Toys, of which the following is a specification.

This invention relates to toys of that class which is usually constructed of paste board 10 or similar material and formed in sections hingedly or detachably connected.

The especial object of the improvements which form the subject matter of this invention is to provide a toy that is capable of 15 being set up or arranged in various ways to produce forms to represent different objects such as houses, stalls, tents, etc.

A further object is to provide a hinged connection for the various sections that will 20 permit the latter to be bent or turned in different directions and to be maintained in the positions to which they are moved.

A still further object is to provide for a form of connection for the various sections 25 that will permit them to be folded flatwise in as small a compass as possible.

Other objects of general utility and economy of construction are secured through the improvements hereinafter described.

30 In the accompanying drawing:—Figure 1 is a perspective view showing one application of my invention; Figs. 2 and 3 are plan views showing adaptations of my invention; Fig. 4 shows in plan view the application 35 of a separable member, and Fig. 5 is a sectional fragmentary detail on enlarged scale showing the form of hinge to connect the various sections together.

Referring to the details of the drawing, 40 6, 7, 8, and 9, represent different members or sections of card-board which are hingedly connected to form a toy house, shown in Fig. 1. The member 6 is cut out as at 6^a to form an archway and the representation of 45 curtains as 6^b, the necessary design or printed matter being added to complete the illusion. On the sections 7 are printed doors 7^a, or if desired, these doors may be cut out in part by the user of the toy. On the sections 8 are printed representations of pictures, and on sections 9 representations of windows with curtains, and pictures hanging on the wall. It will be understood that 50 any suitable designs may be applied to the 55 opposite sides of these members and that openings may be cut in said members if

preferred; the application of ornamentation or designs to these members not forming a part of my invention.

In Figs. 2, 3, and 4, I have shown different 60 adjustments of the various members and it will be understood that on the faces or sides of these members will be printed matter or they will be embellished with designs suited to the respective shapes in which the 65 members are arranged.

The hinge elements of my invention are shown at 10 and 11 in Fig. 5, and the same consist of any suitable flexible fabric or material stitched or otherwise secured to the 70 edges of the members 6, 7, and 8, by lines of stitching as 13. The hinge securing the left hand member 7 to the corresponding member 8 consists of two separate pieces of fabric 10 placed on opposite sides of the 75 members 7 and 8 and stitched therethrough to said members. The hinge that connects the member 6 with the left hand members 7 and 8 consists of a piece of flexible material folded into U-form and embracing the 80 edge of the member 6 as shown by 11, Fig. 5. This hinge element is also stitched or otherwise secured to the members 6 and is furthermore connected with the hinge members 10 at a point midway between the edges 85 of the members 7 and 8, by a line of stitching as 13. The hinge construction between the central member 6 and the right hand members 7 and 8 is a duplicate of that between the left hand member 7 and the contiguous margins of the adjacent members as 90 above described (see Fig. 4). It will be evident, however, that the said hinge connections may be reversed upon opposite margins of said central member 6 making 95 them "rights" and "lefts", but as such an arrangement would be readily understood and easily carried out by any one skilled in the art without the exercise of inventive skill, the said arrangement is not illustrated. 100

It will be understood that where there are only two members connected, the hinge will be constructed as shown by 10 in Fig. 5, but where there are three or four members, the hinge 11 will be utilized and connected 105 with the hinge 10, 10, as shown in Fig. 5.

It will be obvious that instead of using stitching for connecting the hinge members to each of the sections 6, 7 and 8, I may use paste or glue.

In Fig. 4, I have shown a detachable member or section as 14, through which are

slots 15 which are adapted to receive tongues 16 formed along the edges of the members 8 and 9. These tongues may be readily inserted in and removed from said slots in a manner well understood in this class of devices.

For the purpose of this application for patent, I have shown but a few of the various arrangements of which the members 6, 7, etc. are capable and have only indicated one form of ornamentation but it will be apparent that many other combinations may be made.

Having thus described my invention I claim:

A toy device consisting of a series of rigid sheets connected in lineal order by hinges of flexible material, one of said sheets hav-

ing an opening therethrough, coöperating members hingedly attached by one margin 20 along the junctions of said sheets, in combination with a detachable member having slots therein adapted to receive projections on the free margins of said members and the end sheets, the said sheets, members and 25 detachable member adapted to represent the walls of a house and coöperating to form the sides of rectangular compartments open above and below.

In testimony whereof I affix my signature 30 in the presence of two witnesses.

LEONARD C. BAILEY.
